J. W. BOWERBANK

BOILER

Filed April 5, 1924

INVENTOR:

John Wainwright Bowerbank
By: Chatwin & Company
Atty.

UNITED STATES PATENT OFFICE.

JOHN WAINWRIGHT BOWERBANK, OF KIDDERMINSTER, ENGLAND.

BOILER.

Application filed April 5, 1924. Serial No. 704,539.

This invention relates to boilers, which have the advantage of effecting a very quick boiling of water, a continuous and violent circulation and an effective distribution of the water upon and through the contents, and wherein the steam generated in said boiler may be passed to a suitable drying apparatus or other similar appliance by a conduit leading from the cover, such conduit also serving to return any condensation water from such other apparatus, to the boiler. Finally additional heat may be delivered to such other apparatus through a conduit connected with the outer shell of the washing boiler whereby the waste gases from the heating medium are conveyed to an appropriate passage or chamber of the additional apparatus.

The object of this invention is to improve boilers, as above described, by providing them, with a groove about the upper edge of the surrounding casing so that the lid can constitute therewith a water seal and, further, to construct the steam off-take pipe with a recess encompassing its orifice to enable a water-sealed connection with a pipe extension to be made.

In order that the invention may be fully understood and readily carried into effect I will now describe the same with reference to the accompanying drawings, in which:

Figure 1 is a part vertical section of the washing boiler complete; Fig. 2 is a plan; and Fig. 3 is an enlarged sectional view showing a water seal gutter and its connection to the boiler and casing.

In these drawings, 1 is a casing of suitable metal supported on legs 2 and provided with an asbestos or similar insulating lining 3* and an inner protecting metal sheet 3 for the asbestos, the asbestos and the inner sheet 3 being advantageously held together by a beaded edge 4 on the outer casing, or otherwise in any usual manner.

On top of the casing is secured, by brazing or otherwise, a ring 5 formed with a gutter 6 and a depending flange 7 the upper edge 7* of which is advantageously kept below the top surface of the ring 5 to ensure that water in the gutter overflows into the boiler.

The boiler shell proper 8 which advantageously tapers slightly, is secured to the flange 7 by appropriate means and is provided with a plurality of copper or other

projections, studs, rivets or the like 9, distributed over the bottom surface. The lid consists of a ring or annulus 10 adapted to fit in the gutter 6, a cover plate 11 being formed integral with said annulus 10 and 60 having a sight aperture 12 of glass, if desired, so that inspection of the inside of the boiler may be had without the need of raising the cover thereby occasioning loss of steam.

A heating burner preferably of the type described in my co-pending application filed conjointly with the present application, is adjustably secured to the legs as explained in my previous specification and in 70 such a manner that the heat retaining ring 13 provided on the base plate 14 which is fitted with the locking device 15 for engagement with apertures in the legs 2, may be brought up closely against the beaded 75 edge 4 of the casing 1 and that the flame from the burner may play upon the projections or rivets 9 of the boiler proper 8 thus effectively transmitting heat to the contents. The burner proper which is disposed centrally within the ring 13 may be gas, oil or electric as desired without departing from 80 the spirit of the invention.

The boiler proper 8 is fitted with a water circulating device indicated generally by 85 the reference numeral 16 of the character described and claimed in my co-pending application filed conjointly with the present application and wherein a base plate 20 of double conical form acts as a kind of geyser 90 so as to quickly produce hot water and steam which ascends a central tube 21 and is ejected through a series of angularly disposed apertures 22 situate near the top of said central tube. This water circulating 95 device is secured to the bottom of the boiler 8 by means of a number of bolt-devices comprising a pin or bolt 17 upon a lug 18 engaging a short sleeve 19 fixed beneath plate 20. One of such devices is indicated 100 in dotted lines in the drawing, but two or more are preferably employed, the apparatus being locked or unlocked by slightly turning same so that a sliding bolt 23 fitted on the side of the boiler 8 can be engaged 105 with a sleeve 24 provided on the double conical base 20. A tap 27 in the bottom of the boiler enables hot water to be drawn off when desired.

Steam from the boiler 8 may be con- 110

ducted through a conduit 25 to any other apparatus which it may serve to heat, such as a drying drum and condensation water may return to said boiler 8 through the same conduit, for which purpose a water seal 26 in the form of a gutter around the mouth of the conduit 25, is provided so forming an effectively good joint preventing the escape of steam at this point. Waste 10 heat from the heating medium is conducted through an aperture 28 provided in the casing 1.

It will thus be appreciated that a boiler such as described above being possessed of 15 manifold devices for utilizing the heat of the burner to the fullest possible extent, will be capable of generating large quantities of steam, especially if provided with the water circulating device as mentioned above. A

20 good deal of this steam will condense on the lid which is comparatively cool, whilst

the remainder may pass away by the lateral conduit therein to a steam up-take and the provision of gutters at the point where the lid fits on to the boiler and also on to the 25 up-take enables the condensation water to return to the boiler and provides water seals which prevent the escape of steam or water at any point whilst allowing the lid to be readily removed or affixed as desired. 30

I claim:

In combination, a boiler and a supporting casing, a ring secured to the top edge of said supporting casing; said ring being provided on its upper side with inner and outer 35 flanges, forming a gutter, and having a depending flange to engage the inner surface of the boiler; the top of said inner flange being slightly lower than the top of said outer flange.

JOHN WAINWRIGHT BOWERBANK.
